(57) **CLAIM**

The ornamental design for a wig grip band, as shown and described.

DESCRIPTION

FIG. 1 is a front perspective view of a wig grip band, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a view of the wig grip band shown in use.

The evenly spaced broken lines depicting portions of the wig grip band are for illustrative purposes and forms not part of the claimed design.
